UNITED STATES PATENT OFFICE.

JAMES FRANCIS ROWLEY, OF CHICAGO, ILLINOIS.

ARTIFICIAL FOOT.

1,319,491.

Specification of Letters Patent. Patented Oct. 21, 1919.

Application filed November 19, 1917. Serial No. 202,776.

To all whom it may concern:

Be it known that I, JAMES FRANCIS ROWLEY, a citizen of the United States of America, and a resident of Chicago, county of Cook, and State of Illinois, have invented 5 certain new and useful Improvements in Artificial Feet, of which the following is a specification.

The main objects of this invention are to 10 provide an improved artificial foot; to provide an improved form and arrangement of cushioning means for yieldingly resisting the relative movements of the articulated parts of the foot and absorbing the shocks incident 15 to the tread of the foot and the shifting of the weight from one part of the foot to the other during the act of walking; and to provide an improved construction of the core part of said foot.

20 An illustrative embodiment of this invention is shown in the accompanying drawings, in which—

Figure 1 is a sectional elevation of the improved form of foot.

25 Fig. 2 is a detail showing a modified arrangement of the forward cushioning means.

In the specific embodiment herein shown, 30 the foot comprises a leg member or shin section and a foot core 2 articulated thereon by means of a hinge consisting of a bolt 3 and a bolt 4 connected together by a pin 5 which is journaled on the ball bearings 6.

The shin section 1 is hollowed out so as 35 to provide a socket 7 tapered at the lower end wherein a plug 8 is wedged, which plug provides a support for the bolt 3. A base member 9 extends across the bottom of the shin section and coats with the plug 8 for supporting the bolt 3. The lower face of 40 the base 9 forwardly of the hinge connection is substantially horizontal, whereas rearwardly of the hinge connection it is inclined upwardly and rearwardly.

The foot core 2 is embedded in a foot 45 form or body 10 made of sponge rubber and conforming to the general shape of the human foot. The upper face of this foot core 2 is substantially horizontal and parallel with the lower face of the base part 50 9 forwardly of the hinge. The lower face of the foot core 2 adjacent to the front is concave at 11 and inclined downwardly and rearwardly so as to provide a kind of recess or pocket which tends to resist the 55 spreading or creeping of the sponge rubber

along the core when the pressure is upon the ball of the foot.

The improved cushioning means comprises a spring-rubber block 12 and a spring-rubber disk 13 interposed between opposed 60 faces of the core 2 and shin base 9 at opposite sides of the hinge. These springs are formed of firm live rubber so that while they are capable of yielding, they offer considerable resistance, and as soon as the pressure is relieved, they resume their normal shapes.

The block 12 is preferably of cylindrical form and extends through a hole near the rear end of the foot core 2 and is slightly inclined forwardly, at an angle to the vertical. The upper end of this cylindrical block is seated in a recess 14 formed in the under face of the base part 9. The lower end 15 is embedded in the sponge rubber 75 which forms the heel portion of the foot form 10.

The disk 13 is seated in a comparatively deep recess 16 formed in the foot core 2, and in a shallow recess formed in the base part 80 9 by means of which the disk is secured against dislodgment. An aperture or opening 18 is formed in the disk 13 which permits the disk to be expanded or distorted laterally into said opening when said disk is 85 compressed axially between said core and base.

In the modification shown in Fig. 2, the base part 9 has a pin 19 formed thereon which fits in the opening 18 of the ring-shaped disk 13, and the recess in the core 2 is greater in diameter than the disk, so that when said disk is compressed, the expansion or distortion occurs around the periphery of the disk.

These two pieces of live spring-rubber located between the articulated parts of the foot at opposite sides of their connection, serve to yieldingly resist the relative shifting of said parts and to absorb the shocks 100 which occur during the process of walking. Being formed of firm live rubber, they will yield to the pressure or shocks and materially absorb the same, but as soon as such pressure or shocks are removed, they will resume their normal form, thus insuring the normal relation of the articulated parts of said foot.

Although but one specific embodiment of 110 this invention has been herein shown and

described, it will be understood that numerous details of the construction shown may be altered or omitted without departing from the spirit of this invention as defined by 5 the following claims.

I claim:

1. An artificial foot, comprising a leg member, a foot core hingedly mounted below said leg member, and a spring-rubber 10 cushion extending above and below said core so as to bear directly between said leg member and the lower part of the foot.
2. An artificial foot, comprising a shin section, a foot core hingedly mounted 15 thereon, a foot form supported on and surrounding said foot core, and a block of spring-rubber extending through the rear end of said foot core and having the upper end bearing against said shin section and the lower end embedded in the heel portion of said foot form.
3. An artificial foot, comprising a shin section, a foot core hingedly mounted 20 thereon, a foot form supported on and surrounding said foot core, and a spring-rubber disk interposed between the opposed faces of said shin section and foot core, said foot core having a comparatively deep recess and

said shin section having a comparatively shallow recess within which said disk is 30 adapted to fit, so as to be secure against dislodgment, said disk having a central opening formed therein whereby said disk is adapted to expand laterally when compressed axially between said core and shin 35 section.

4. An artificial foot, comprising a shin section, a foot core hingedly mounted thereon, a foot form supported on and surrounding said foot core, a block of spring- 40 rubber extending through the rear end of said foot core and having the upper end bearing against said shin section and the lower end embedded in the heel portion of said foot form, and a spring-rubber disk interposed between the opposed faces of said shin section and foot core forwardly of the hinge connection, said core being recessed 45 to receive said disk to secure it against dislodgment but permitting the lateral expansion of said disk when compressed axially between said core and shin section.

Signed at Chicago this 15th day of Nov., 1917.

JAMES FRANCIS ROWLEY.
